UNITED STATES PATENT OFFICE.

FREDERICK W. STEWART, OF COLDWATER, MICHIGAN.

WRENCH.

SPECIFICATION forming part of Letters Patent No. 630,421, dated August 8, 1899.

Application filed October 1, 1898. Serial No. 692,364. (No model.)

To all whom it may concern:

Be it known that I, FREDERICK W. STEWART, a citizen of the United States, residing at Coldwater, in the county of Branch and State of Michigan, have invented a new and useful Wrench, of which the following is a specification.

The invention relates to improvements in wrenches.

10 The object of the present invention is to improve the construction of wrenches and to provide a simple and comparatively inexpensive nut-wrench in which the movable jaw may be readily placed contiguous to the nut or other object to be clamped and quickly adjusted to exert the desired pressure on such object.

15 The invention consists in the construction and novel combination and arrangement of parts, as hereinafter fully described, illustrated in the accompanying drawings, and pointed out in the claims hereto appended.

20 In the drawings, Figure 1 is a longitudinal sectional view of a wrench constructed in accordance with this invention. Fig. 2 is a transverse sectional view. Fig. 3 is an enlarged detail sectional view illustrating the manner of connecting the thumb-piece or head of the adjusting-screw to the body portion thereof. Fig. 4 is a longitudinal sectional view illustrating a modification of the invention.

25 Like numerals of reference designate corresponding parts in all the figures of the drawings.

30 1 designates a stationary jaw coöperating with a sliding jaw 2, which is mounted on a shank 3, having concave side faces 4 and provided with a rounded rear face 5. The shank is provided at its front edge with shouldered 35 teeth 6, adapted to be engaged by a dog 7, which is housed within a casing or extension 8 of the movable jaw, and the latter, which is provided with an opening for the passage of the shank 3, has the same enlarged toward its inner end, whereby the movable jaw is adapted to swing laterally of the shank sufficiently to carry the teeth 9 of the dog into and out of engagement with the teeth 6 of the shank. The dog is carried by the movable jaw in its 40 movement transversely of the shank, and the teeth 6 and 9 are retained in engagement with each other by means of a coiled spring 10, lo-

cated at the inner end of the movable jaw and interposed between the back of the same and the rear face of the shank. The back of the 55 sliding jaw is provided with a recess, forming a seat for the coiled spring 10, and by compressing the latter the dog may be readily disengaged from the shank, and the sliding jaw can then move freely on the latter to bring 60 it adjacent to or carry it away from an object and to enable it to be quickly adjusted approximately to such object. The back portion of the sliding jaw is recessed between the ends, as shown at 11, to lighten the construc- 65 tion.

70 The sliding movement of the jaw 2 on the shank permits the jaws to be arranged close to the opposite sides of a nut or other object, and when the teeth 6 and 9 are engaged with each other the sliding jaw drops back slightly. The desired pressure on the object is effected by means of a longitudinal adjusting-screw 12, having a threaded portion 13, engaging a correspondingly-threaded opening or socket 75 14 of the jaw 2. The screw has a smooth portion 15, which passes through an opening 16 of the dog, and it is reduced to form a shoulder 17 for engaging the inner or front end of the dog, whereby the screw is adapted to bear 80 against the dog and force the sliding jaw forward into engagement with the object to be clamped. The smooth portion 15 is further reduced at its center at 18 to provide an intervening annular space between it and the 85 dog to reduce the friction between the screw and the latter to a minimum. The outer end of the screw is reduced and threaded at 19, right-hand screw-threads being provided and a milled head or thumb-piece 20, which is 90 correspondingly threaded, is arranged on the reduced portion 19. In order to lock the head or thumb-piece on the adjusting-screw, a left-hand-threaded screw 21 is employed and engages a socket 22, formed in the reduced end 95 of the screw 12 and provided with left-hand-screw-threads. The head of the screw 21 engages the thumb-piece or head 20 at the outer face thereof and effectually prevents the same from accidentally unscrewing.

100 The casing of the sliding jaw extends beyond the dog, and a sleeve 23 is interposed between the head or thumb-piece 20 and the adjacent end of the dog and forms a shoulder

for engaging the latter. By arranging the dog between the shoulder 17 and the sleeve a swivel connection between it and the screw is provided. The casing is provided with a transverse fastening device 24, consisting of a rivet or the like and passing through the space between the dog and the head or thumb-piece 20. The movable jaw and the casing may be constructed of a single piece of metal, as illustrated in the accompanying drawings, or those parts can be made in separate pieces and suitably secured together, if desired.

In Fig. 4 of the accompanying drawings is illustrated a modification of the invention in which the adjusting-screw 25 is swiveled to the sliding jaw and engages screw-threads of the dog, the screw-threads 26 of the adjusting-screw being located between the ends thereof, as shown. The inner or rear end of the screw is provided with a head or thumb-piece, as before described, and the forward or inner end of the screw is provided with a smooth bearing portion or head 27, arranged in a bearing-socket 28 and retained therein by a screw 29, mounted on the sliding jaw, as shown, and engaging an annular recess cut in the screw adjacent to the head or bearing portion 27. In order to reduce the friction to a minimum, an antifriction-ball 30 is interposed between the end of the screw and the end of the socket 28. By rotating the adjusting-screw 25 the sliding jaw may be advanced independently of the dog for the purpose before explained.

The invention has the following advantages: The wrench is simple, inexpensive, strong, and durable and is adapted to have its sliding jaw quickly moved along the shank to bring it adjacent to the nut or other object to be clamped, and the screw will permit the sliding jaw to be further adjusted to secure the necessary pressure. The spring is housed within the casing of the movable jaw, and the parts are compactly arranged and not liable to get out of order.

Changes in the form, proportion, and minor details of construction, such as varying the arrangement of the adjusting-screw and omitting the ball shown in the modification, may be resorted to without departing from the spirit or sacrificing any of the advantages of this invention.

What is claimed is—

1. In a wrench, the combination of a toothed shank, a sliding jaw provided with a threaded socket and having a hollow casing, a dog mounted within the hollow casing and engaging the shank and adapted to be carried away from the same by the movable jaw, and a screw engaging the threaded socket of the jaw and swiveled to the dog, substantially as described.

2. In a wrench, the combination of a toothed shank, a sliding jaw mounted thereon and capable of a limited movement laterally thereof, said jaw being provided with a threaded socket, a dog engaging the shank, and a screw swiveled to the dog and engaging the threaded socket of the jaw, substantially as described. 65

3. In a wrench, the combination of a toothed shank, a sliding jaw mounted thereon, provided with a hollow extension or casing and having a limited movement transversely of the shank, a dog housed within the casing 75 and engaging the shank, a screw connecting the dog and the jaw, said screw and dog being carried by the jaw in its transverse movement, and a spring for holding the dog normally in engagement with the shank, substantially as described. 80

4. In a wrench, the combination of a shank, a sliding jaw, a dog mounted on the sliding jaw and engaging the shank and provided with an opening, an adjusting-screw having 85 a threaded portion to engage the jaw, and provided with a smooth portion passing through the opening of the dog, said screw having a shoulder to engage the inner end of the latter, a sleeve arranged on the outer end of the screw and engaging the dog, and a head fitting against the sleeve, substantially as described.

5. In a wrench, the combination of a shank, a sliding jaw having a hollow casing and capable of a limited movement transversely of the shank, a dog housed within the casing and carried by the jaw in its transverse movement, a screw swiveled to the dog and engaging the jaw, and a fastening device passing 100 through the sides of the casing and located at the outer end of the dog, substantially as described. 95

6. A wrench having an adjusting-screw provided with a reduced portion having right-hand screw-threads, said screw being also provided with a cylindrical socket having left-hand screw-threads, a head having a threaded opening and engaging the right-hand screw-threads of the reduced portion of 110 the screw and projecting laterally beyond the same, and a left-hand-threaded screw arranged in said socket and having its head engaging the said head and being of less diameter than the same, substantially as described. 115

In testimony that I claim the foregoing as my own I have hereto affixed my signature in the presence of two witnesses.

FREDERICK W. STEWART.
